PENCIL SHARPENER

Application filed July 10, 1928. Serial No. 291,669.

Our invention relates to pencil sharpeners, and particularly to such pencil sharpeners in which rotary cutters are used to obtain a desired pencil point.

5 Pencil sharpeners of known constructions furnish conical or substantially conical pencil ends, in which the lead terminates in a point. A sharp point of a pencil is known to wear off quickly in use, and pencils so sharpened therefore need frequent repointing, at least when they are to be used for drawing accurate or fine lines. Moreover a sharp pencil point may break off easily.

10 For these reasons it is common drawing room practice to regrind a pencil by hand not to a single point, but rather to an edge, as will be further described hereafter. A pencil preserves a keen edge much longer than it can preserve a single sharp point, and therefore continues much longer to give fine and accurate lines, before it needs to be re-sharpened.

15 One object of the present invention is to provide a pencil sharpener which furnishes pencil ends terminating in an edge, especially in a rounded edge.

20 Another object is to provide a pencil sharpener suited to furnish a pencil point of great strength. A further and important aim is to provide a pencil sharpener suited to furnish an oval pencil point which is reinforced by projections of the wooden case of the pencil.

25 A still other aim is to provide a pencil sharpener of very simple and rigid construction which is suited to give the novel performance described.

30 Another object is to devise a pencil sharpener having special provision for preventing the pencil point from breaking in the sharpening operation, and which furnishes a very smooth cut.

35 Further objects will appear in the course of the specification and from recital of the appended claims.

40 Embodiments of our invention are illustrated in the accompanying drawings, in which

45 Fig. 1 is a sectional view of one embodiment of a pencil sharpener constructed in

accordance with our invention, the section being taken along lines 1—1 of Fig. 2.

Fig. 2 is a front elevational view corresponding to Fig. 1.

Fig. 3 is an end view of the pencil sharpener 55 shown in Fig. 1, the view being taken looking at side 2.

Fig. 4 and Fig. 5 are diagrammatic views of two different positions of an eccentrically mounted cutter in engagement with a pencil 60 end, illustrative of a principle of the present invention.

Fig. 6 and Fig. 7 are diagrammatic views of a cutter engaging a pencil end, the axis of rotation of said cutter being inclined to the 65 center line of the cutter body.

Fig. 8 and Fig. 9 are diagrammatic views of a cutter engaging a pencil end, illustrative of the disposition shown in the Figures 1 to 3. 70

Fig. 10 is an end view of an individual cutter.

Fig. 11 is a diagrammatic view of another embodiment of the present invention.

Fig. 12 is a side view corresponding to 75 Fig. 11 of the pencil end and of the cutter, the view being taken at right angles to the plane cutting surface.

Fig. 13 is a gear diagram illustrative of a way of gearing up two cutters at the ratio 80 of one to two with respect to a member concentric with the pencil, while avoiding interference between the two pinions forming part of the cutters.

Fig. 14 is a gear diagram similar to Fig. 85 13 and illustrative of the disposition used in the Figures 1 to 3.

Referring to the Figures 1 to 3, the numeral 11 denotes a casing having a socket 12, which may be fastened to any suitable support, such as a table, by means of screws disposed in the holes 13. Casing 11 contains a bearing 14 rotatably holding an extension 15 of a planet carrier 16. The latter may be turned on its axis by means of a crank 17 95 having a handle 18.

Planet carrier 16 contains two planets 18, 19, rotatable on axes 20, 21, which in the present instance are angularly disposed to the axis (15') of the planet carrier 16 and 100

offset from said axis. The planets 18, 19 are in the form of milling cutters and contain pinions 22, 23 rigidly connected with them, which mesh with an internal gear 24 secured to casing 11. As the crank 17 is turned, the planets 18, 19 move bodily about axis 15', and, owing to the mesh between the planetary pinions 22, 23 and the stationary internal gear 24, turn on pins 20, 21, which are screwed to the planet carrier 16 with their ends 25.

The pencils to be sharpened are introduced through opening 26 coaxial with axis 15' and advanced into engagement with the milling cutters 18, 19, and are prevented by hand from turning. The said milling cutters then form the end of the pencil in their planetary motions.

We will now proceed to particularly describe the novel principles and features characterizing the present invention.

According to our invention the centers of the cutter surfaces (18, 19) differ from the centers 20, 21 of rotation. An object here-
25 with attained will first be described with reference to Fig. 4 and Fig. 5.

In these figures, the axis 20 of rotation is shown offset from the center 30 of the surface of the cutter body 18, and parallel to said center. The surface of cutter body 18 is a cylindrical surface in the instance illustrated. The axis of rotation intersects the axis 15' of pencil 31 in a point 32, which maintains its position during the planetary motion of the cutter about axis 15'. In Fig. 4 the position of the cutter 18 is illustrated in which the axis of rotation 20 is inside of the center 30 of the cutter surface, and where the centers 20, 30 and 15' are all lying in the same plane. Fig. 5 illustrates a position, in which the cutter 18 has been turned by half a revolution as compared with the position shown in Fig. 4, and where the axis of rotation 20 is outside of the center 30, the centers 20, 30 and 15' again lying all in the same plane.

In accordance with our invention, the ratio between the rotation of the cutter 18 on its axis 20 and the planetary rotation of the cutter body on axis 15' is two to one. This corresponds to a number of teeth on internal gear 24 twice as large as the number of teeth of the pinions 22, 23 in the embodiment of our invention illustrated in Fig. 1 to Fig. 3. With the said ratio of two to one, the cutter surface approaches the center of the pencil 31 (Fig. 4 and Fig. 5) to a minimum distance twice per planetary revolution on center 15'; and it draws away from the pencil center to a maximum distance also twice per revolution on center 15'. The position corresponding to a maximum distance between the cutter surface 18 and the axis 15' of the pencil is illustrated in Fig. 4; and Fig. 5 shows the position of minimum distance. The end 33 of pencil 31 is formed as a surface enveloped

by the various relative positions of the cutter surface (18) and is found to be of oval form. The two broad sides of the oval are formed when the cutter 18 is in a position near to the center of the pencil, Fig. 5, which is attained twice per planetary revolution about axis 15', and the two narrow sides are formed when the cutter 18 is in a position remote from the center of the pencil, see Fig. 4. Fig. 4 moreover accords a view of the broad side of the pencil end, and Fig. 5 furnishes a view of the narrow side of the pencil end.

It is particularly noted that the pencil lead 34 resulting from an eccentric cutter 18 terminates in an edge 34', that is to say in a rounded line, and moreover, that the wooden pencil case 35 reinforces the lead with two extensions 36 adjacent the narrow sides of the pencil end, see Fig. 4. These extensions 36 are naturally and automatically formed in the sharpening operation without further provision.

Fig. 6 and Fig. 7 illustrate a slightly modified disposition of the axis of rotation 20 relatively to the center 30 of the cutter surface. The two centers 20 and 30 are angularly disposed to each other and intersect in a point 38 on the side of the cutter which forms the portion where the pencil end meets the outside surface of the pencil. The cutter surface contains therefore an eccentricity changing lengthwise of the cutter. The said eccentricity is maximum adjacent the lead 34 of the pencil, and it is reduced to zero adjacent the above said position, which is formed truly circular. The form of the lead end 34 itself obtained from the disposition illustrated in Fig. 6 and Fig. 7 is substantially the same as in the disposition shown in Fig. 4 and Fig. 5, when the eccentricities of the cutter surfaces are the same adjacent said lead end.

The term lead is used in the present specification with the broad meaning of pencil filling, which may be of any suitable material, especially also graphite mixtures.

Fig. 8 and Fig. 9 illustrate the general disposition of cutter center 30 and axis of rotation 20 as used in the embodiment of our invention illustrated in the Figures 1 to 3. Along the whole length of the cutter, its center 30 is offset from the axis of rotation 20, and the amount of offset increases towards the side adjacent portion 40, where the pencil end meets the outside surface of the pencil. The center lines 30 and 20 may be disposed to either intersect in a point outside of the cutter body, or, if so desired, they may be disposed askew, so that they do not intersect at all.

Fig. 8 is a view looking at the broad side of pencil 31, with the surface of cutter 18 at a maximum distance from the center of the pencil. Fig. 9 is a view looking at the narrow side of pencil 31, with the cutter sur-

face in minimum distance from the pencil center. The disposition indicated in Fig. 8 and Fig. 9 permits to obtain extensions 36 of increased strength. For convenience the cutter surface 18 and axis of rotation 20 are shown as if said axis would intersect the axis 15' of planetary motion, whereas in the embodiment shown in Fig. 1 to Fig. 3, to which Fig. 8 and Fig. 9 correspond, the axes 20 are slightly offset from axis 15'.

5 Cutter 18 is preferably made in the form of a milling cutter having cutting edges disposed in a surface of revolution, such as a cylindrical surface in the instance illustrated in the Figures 1 to 8. The said cutting edges are formed by flutes or gashes 41 (Fig. 10), which preferably extend along spirals or helices 42.

10 Adjacent opening 26, Fig. 1 and Fig. 3, gripping means 43 are disposed, for securely holding the pencil to be sharpened, while yet permitting an advance of the pencil in the direction of its axis.

15 The said gripping means consist of an elastic steel ring 44 containing two projections 45 forming jaws 46. The said projections 45 as well as further projections 47 disposed at right angles thereto are guided in radial slots of a ring 48 secured to casing 11.

20 Under the influence of the spring means constituted by steel ring 44, the jaws 46 tend to approach each other and to securely grip a pencil introduced through opening 26. Prior to introducing a pencil, ring 44 is

25 pressed together by hand in a manner that the projections 47 are radially approached to each other in the directions of arrows 49. As the curve of the ring 44 gets flatter adjacent said projections, the other projections 45

30 are moved outwardly, inasmuch as the ring tends to preserve its length. The jaws 46 then give free passage to the pencil being introduced. The pencil is securely gripped, as soon as the hand pressure on ring 44, adjacent projections 47, ceases.

35 In the embodiment of our invention diagrammatically illustrated in Fig. 11 and Fig. 12, the active surface of cutter 18 is a plane disposed at an acute angle 50 to its axis of rotation 20. A view at right angles to said plane is illustrated in Fig. 12. Cutter 18 is geared up with a stationary tapered sun gear 51 concentric with pencil 31 by means of a hypoid pinion 52.

40 The ratio between gear 51 and pinion 52 is again two to one, as in the embodiments already referred to. This ratio of two to one is chosen to obtain the desired oval form of the pencil end. The cutter 18 is made to 45 perform a planetary motion about the axis of the pencil, of the general character previously described.

45 In this embodiment as well as in the one already described, the planetary motion could be substituted by rotation on two fixed

centers, if so desired, namely on the axis 20 of the cutter 18 and on a center 15' coaxial with the pencil, as is readily understood by those skilled in the mechanical art.

50 Milling cutter 18 is preferably provided with curved or spiral flutes 53 forming cutting edges 54 which are substantially perpendicular to the line of contact 55 between the pencil and the cutting plane of milling cutter 18, see Fig. 12. The curves 54 may for 55 instance be made involutes, having a base circle 56. The cutter is rotated in the direction of arrow 57, so that the cutting edges 54 act backwardly from the lead edge towards the main body of the pencil, while remaining substantially perpendicular to the generatrices of the oval pencil end. The cutting pressure is then always directed backwardly in a direction to effect a minimum bending moment on the pencil, so that there 60 is no danger at all to break off the lead of the pencil. Also when the cutting edges (54) of the milling cutter 18 are made straight, they are preferably disposed at such inclination relatively to radial lines, 65 that they are perpendicular to the line of contact 55 at least adjacent the lead end 34.

70 When a single milling cutter 18 is used, or when its axis 20 of rotation is disposed at a large angle (50) to the axis (15') of planetary rotation, as in the embodiment diagrammatically illustrated in Fig. 11 and Fig. 12, no difficulty is experienced of obtaining a ratio of two to one with known means.

75 When however two cutters are used having axes 20, 21 parallel to the axis 15' of the planetary motion, or having axes 20, 21 inclined by small angles relatively to axis 15', as in the embodiment illustrated in the Figures 1 to 3, then it is found somewhat difficult to prevent the two pinions (22, 23) connected with the two cutters from interfering with each other, when employing conventional gear design. This difficulty is illustrated in Fig. 13 for cutters having axes 80 20, 21 parallel to axis 15'.

85 At a two to one ratio the pitch circles 58 of the pinions are half the size of the pitch circle 60 of internal gear 24, and they contact with each other at center 15'. In 90 conventional practice gear teeth are proportioned so that the active tooth surfaces extend equal amounts above and below the pitch circles, (58, 60). In other known cases the pinion is provided with teeth extending by 95 a larger amount outside of the pitch circle than inside of the pitch circle. The pinion contains then what is commonly called increased addenda, while the mating gear contains reduced addenda.

100 In the present case we provide teeth 61 on the pinions extending wholly inside of the pitch circles 58, that is to say teeth 61 which consist solely of dedenda, so that the outside diameter of the pinions is slightly smaller 105 110 115 120 125 130

than their pitch diameter. Moreover we increase the pressure angle 62 or inclination angle 62 of the line of action above the standard amount, and thereby obtain a satisfactory duration of action also when the tooth number of the pinions is small.

The aspect of the gear problem does not change materially, when the axes 20, 21 of rotation of the pinions 18, 19 are somewhat tilted with respect to central axis 15', see Fig. 14. This disposition corresponds to the embodiment shown in the Figures 1 to 3. The pinions are provided with increased dedenda, so that they do not interfere with each other adjacent axis 15', and are further provided with increased pressure angles. Preferably the teeth 61 of the pinions are made straight and parallel to their axes of rotation, whereas the teeth 63 of internal gear 64 (Fig. 14) are made slightly helical.

In either case (Fig. 13 and Fig. 14) the outside diameter of the pinions is less than one half of the root diameter of the internal gear.

Pencils provided with an oval end, put within easy reach through our novel pencil sharpener, are not confined to use in drawing rooms, but may be generally used. They are convenient for writing as well as for sketching. They give shades or heavy lines without effort, and they are stronger and longer wearing than pencils sharpened to a single point.

Numerous modifications may be made in our invention without departing from its spirit, by simply applying the general knowledge of the art. For definition of the scope of our invention we rely on the appended claims.

What we claim is:

1. A pencil sharpener, containing a plurality of cutting edges, means for moving said cutting edges relatively to a pencil in paths differently located relatively to the axis of said pencil, and means for effecting different angular positions between said pencil and the relative paths of said cutting edges.

2. A pencil sharpener, containing a plurality of cutting edges rotatable on an axis, means for moving said cutting edges relatively to a pencil in paths differently located relatively to the axis of said pencil, and means for effecting different angular positions between said pencil and the relative paths of said cutting edges.

3. A pencil sharpener, containing a cutting member provided with a plurality of cutting edges, means for rotating said member, means for providing turning motion between said member and a pencil on an axis coinciding with the center line of said pencil to effect contact between the pencil and the surface of said cutting member along a line moving around the center line of said pencil, and means for displacing said line relatively to the center line of the pencil.

4. A pencil sharpener, containing a milling cutter provided with cutting edges disposed in a surface of revolution, the center line of said surface being offset from the axis of rotation of said cutter, means for rotating said cutter on said axis, and means for effecting turning motion between said cutter and a pencil on an axis coinciding with the center line of said pencil, said turning motion being timed up with the rotation of the cutter on its axis.

5. A pencil sharpener, containing a pair of milling cutters provided with cutting edges disposed in surfaces of revolution of straight profile in axial section, the center lines of said surfaces being offset from the axes of rotation of said cutters, means for centering a pencil, means for rotating said cutters on their respective axes, and means for bodily moving said cutters in a planetary path about an axis coinciding with the center line of said pencil in timed relation to the rotation of said cutters on their axes.

6. A pencil sharpener, containing a pair of milling cutters provided with cutting edges disposed in cylindrical surfaces, the center lines of said surfaces differing from the axes of rotation of said cutters, means for rotating said cutters on their respective axes, means for bodily moving said cutters in a planetary path about an axis coinciding with the center line of a pencil introduced for sharpening, and means for timing up the rotation of said cutters and their planetary motion at a ratio of two to one, so that the cutters turn twice on their axes per planetary revolution.

7. A pencil sharpener, containing a milling cutter having a center line differing from its axis of rotation, means for rotating said milling cutter on said axis, means for effecting turning motion between said milling cutter and a pencil on an axis coinciding with the center line of the pencil, and means for timing up said turning motion and the rotation of said cutter in a manner that two revolutions of the cutter take place per complete revolution about the center line of the pencil.

8. A pencil sharpener, for producing an oval pencil end, consisting of a rotary cutter, means for bodily moving said cutter about an axis coinciding with the center line of a pencil, and gears operatively connecting said cutter with a stationary casing at a ratio of one to two, the gear connected with said casing having twice the number of teeth of the gear connected with said cutter.

9. A pencil sharpener for producing an oval pencil end, consisting of a rotary cutter, means for rotating said cutter, and means for effecting turning motion between said cutter and a pencil at a ratio of one revolution per two revolutions of the cutter on its axis.

10. In a pencil sharpener, a cutter having cutting edges formed by flutes, the flutes being disposed at such inclination on the sur-

face of said cutter, that they are substantially perpendicular to the line of contact between the surface of the cutter and the end of a pencil adjacent its lead.

5 11. A pencil sharpener for producing an oval pencil end, comprising cutting means, means for centering a pencil, means for moving said cutting means and said pencil relatively to each other in a manner to cover the entire periphery of the pencil with said cutting means, and means for effecting an oval pencil end.

10 12. In a pencil sharpener for producing an oval pencil end, a pair of milling cutters, means for effecting turning motion between said cutters and a pencil, an internal gear meshing at a ratio of two to one with pinions connected with said cutters for timing up said turning motion with the rotation of the cutters on their axes, the outside diameter of the pinions being less than one half of the root diameter of the internal gear.

15 13. In a pencil sharpener for producing an oval pencil end, a pair of milling cutters, means for bodily moving said cutters around a pencil, an internal gear meshing at a ratio of two to one with pinions connected with said cutters for timing up said motion with the rotation of the cutters on their axes, the outside diameter of the pinions being less than one half of the root diameter of the internal gear.

20 14. A pencil sharpener, containing a rotary cutter provided with a plurality of cutting edges, means for moving said cutting edges relatively to a pencil in paths differently located relatively to the center line of said pencil, means for effecting turning motion between said cutter and said pencil about an axis coinciding with the center line of said pencil, and timing means for moving said cutting edges into engagement with said pencil exactly twice per revolution about said axis.

25 15. A pencil sharpener, containing a milling cutter provided with cutting edges disposed in a surface of revolution, said cutter being rotatably mounted on an axis extending inside of said surface and angularly disposed to the center line of said surface, means for rotating said cutter on its axis, and means for effecting turning motion between said cutter and a pencil in timed relation to the rotation of said cutter.

30 16. A pencil sharpener, containing a pair of cylindrical milling cutters rotatably mounted on axes extending inside of the cylindrical cutting surfaces of said milling cutters, said axes being angularly disposed to the center lines of said cylindrical cutting surfaces, means for rotating said cutters on said axes, and means for bodily moving said cutters about a pencil in timed relation to the rotation of said cutters.

35 17. A pencil sharpener, containing a rotary cutter provided with a plurality of cutting

edges, means for moving said cutting edges relatively to a pencil in paths differently located relatively to the center line of said pencil, means for maintaining said pencil centered with spring pressure, means for effecting turning motion between said cutter and said pencil, and timing means for effecting engagement between said cutting edges and said pencil exactly twice per revolution of said turning motion.

40 18. A pencil sharpener, containing a rotary cutter provided with a plurality of cutting edges, said cutting edges having different distances from the axis of rotation of said cutter, means for rotating said cutter on its axis, and means for moving said axis about the center line of a pencil, in timed relation to the rotation of said cutter on its axis.
